UNITED STATES PATENT OFFICE

161,523

PORTABLE POWER-OPERATED SAW

Leonard E. Parker, Chicago, Ill., assignor to Cummins Business Machines Corporation, Chicago, Ill., a corporation of Illinois

Application June 17, 1949, Serial No. 3,377

Term of patent 3½ years

(Cl. D93—3)

To all whom it may concern:

Be it known that I, Leonard E. Parker, a citizen of the United States, residing at Chicago, in the county of Cook and State of Illinois, have invented a new, original, and ornamental Design for a Portable Power-Operated Saw, of which the following is a specification, reference being had to the accompanying drawings, forming part thereof.

Fig. 1 is a side elevational view of a portable power-operated saw showing my new design.

Fig. 2 is an elevational view of the saw looking from the other side.

Fig. 3 is a front elevational view of the saw.

Fig. 4 is a rear elevational view of the saw.

I claim:

The ornamental design for a portable power-operated saw, substantially as shown.

LEONARD E. PARKER.
